UNITED STATES PATENT OFFICE.

DAVID HINDAHL, OF CHICAGO, ILLINOIS, ASSIGNOR TO NATIONAL DUMP CAR COMPANY, A CORPORATION OF MAINE.

CAR-DOOR-ACTUATING MECHANISM.

1,186,097.

Specification of Letters Patent.

Patented June 6, 1916.

Application filed July 6, 1914, Serial No. 849,207. Renewed December 27, 1915. Serial No. 68,947.

To all whom it may concern:

Be it known that I, DAVID HINDAHL, a citizen of the United States, residing at Chicago, in the county of Cook and State of Illinois, have invented certain new and useful Improvements in Car-Door-Actuating Mechanism, of which the following is a specification.

This invention relates to improvements in car door actuating mechanisms.

The object of my invention is to provide a new and improved car door actuating mechanism, and my invention comprises a rotatable shaft, arms rotatably mounted on said shaft and pivotally attached to other arms in turn attached to the dump doors of the car. Fixed to the rotatable shaft are small crank arms arranged to engage the first named arms to effect a rotation thereof when the shaft is rotated to close said doors. These crank arms are further provided with cam faces adapted to engage shoulder portions of the second named arms as the door approaches closed position. These cam faces and shoulders are so arranged that the latter will roll upon the former as the doors are brought to closed position, thereby transferring the load of the doors from comparatively long arms to the shorter crank arms, at the same time limiting, to a great extent, the friction which would ordinarily be present in effecting such a transference of weight. These short crank arms and second named arms are so constructed that the former will effect the positive displacement of the latter from closed position, permitting the doors to open when it is desired to unload the car.

The construction and operation of my device is set forth in the following specification and shown in the accompanying drawings, in which:

Figure 1 is a side elevation of a car showing my invention applied thereto; Fig. 2 is a detail transverse section showing a door in closed position; Fig. 3 is a view similar to Fig. 2 showing a door in open position; Fig. 4 is a detail of the shaft operating mechanism; Fig. 5 is a detail of the door actuating mechanism showing a door in closed position, and Fig. 6 is a detail section along the line 6-6 of Fig. 2.

Like numerals refer to like elements throughout the drawings.

10 designates generally a car having the

side walls 11 secured to side stakes 12, as shown in Fig. 1. Bearing brackets 13 are provided adjacent the lower portion of these stakes 12 and are attached thereto. An operating shaft 14 is provided running longitudinally of the car at the side thereof, this shaft being preferably of non-circular cross section. The sleeves 15, apertured to closely fit shaft 14, are attached thereon by bolts 16 or the like, for additional security. A portion of each of these sleeves 15 closely fits and is rotatably mounted in the brackets 13, thereby insuring proper journaling of the shaft 14 for rotation, notwithstanding its non-circular cross section. Arms 17 are provided at suitable intervals on the shaft 14, these arms being composed of the spaced apart strips 17^a, rotatably mounted adjacent one extremity on the sleeve 15 and held in spaced relation by thimbles 17^b through 75 which extend pins or rivets 17^c, retaining them in place. Other arms 18 are provided, these arms having slots 18^a adjacent one extremity thereof. These slotted extremities of the arms 18 are located between the strips 17^a of arms 17 and a pivotal connection is provided by means of pin 19, shown in Figs. 2 and 5, for example. At their other extremities these arms 18 are attached to a rod or shaft 20.

The car 10 is provided with a plurality of dumping doors 10^a and at the forward edge of each of these doors 10^a on the under side thereof, are attached brackets 21, depending downwardly and outwardly of said doors, each of these brackets being provided with a slot 21^a adjacent their lower extremities. The rod 20 extends through and fits in the slots 21^a, as clearly shown in Fig. 5, for example. The arms 18 each have an extremity fitted on the rod 20. Crank members 23 are provided preferably formed integral with the sleeve members 15 and located between the strips 17^a of arms 17. These crank members are provided with the hook portions 23^a arranged to engage the thimbles 17^b on pins 17^c, as clearly shown in Fig. 2 of the drawings, and are further provided with cam faces 23^b, see Figs. 2 and 3. The arms 18 are cut away or formed with a cut-away portion at 18^b, thereby providing a shoulder 18^c which in turn is provided with a rounded edge or forward portion 18^d, see Fig. 3.

The operation and arrangement of the

above described mechanism is as follows: Rotation in the proper direction is imparted to shaft 14 and crank arms 23, by virtue of their engagement with the thimbles and 5 pins 17^b—17^c, respectively, which operates to rotate the arms 17 with the shaft 14, thereby drawing up the doors 10^a toward closing position, by means of the operation of arms 18. When the doors 10^a approach 10 their closed position the rounded edge 18^a of shoulder 18^c contacts with the cam faces 23^b of the crank arms 23 causing the arms 18 to be drawn upwardly of the car relative to arms 17 until shoulders 18^c rest firmly on 15 the top of crank arms 23, as shown in Fig. 2. This relative movement or sliding of one arm with respect to the other is permitted by means of the slots 18^a in arms 18, as is obvious. As the doors approach closed 20 position, the shoulders 18^c, as explained above, will contact with the cam faces 23^b of crank arms 23 and further movement of the actuating mechanism will result in these shoulders rolling up with and on these cam 25 faces. During this movement a relative or rolling movement of the shoulders 18^c takes place on and with respect to the cam faces 23^b, as will be apparent, inasmuch as the rolling friction is considerably less than 30 sliding or bearing friction and it is obvious that the transfer of the weight of the doors from the arms 17 to the crank arms 23 will be effected with a minimum of frictional resistance.

35 When in the position shown in Fig. 2, which I have termed closed or closing position, a face of the cut-away portion 18^b of arms 18 will lie adjacent to and contact with an edge of the crank arms 23. By means of 40 this arrangement, when it is desired to open the doors, a reverse rotation may be imparted to the shaft 14, whereupon the contact of the crank arms with the arms 18 will operate to move the arms 17 and 18 from 45 the position shown in Fig. 2. I preferably arrange and construct the parts of my device so that when in closing or closed position, as shown in Fig. 2, the centers of support of arms 18, and consequently the doors 50 10^a will lie in substantially vertical alignment with the center of the shaft 14 so as to substantially aid in insuring against accidental movement of the arms from supporting position in which position the load 55 on the doors 10^a is received by the crank arms 23 and consequently the shaft 14. To effect the rotation of the shaft 14, I attach star wheel 30 thereto. Also attached to the shaft 14 adjacent the star wheel 30, is a 60 collar or sleeve 31 upon which is mounted the ring portion 32 of the socket member 33. A pawl or dog 34 is pivoted to the socket member 33 and may be thrown into position 65 engaging the star wheel 30 so that when a lever or handle is placed in the socket mem-

ber 33, proper oscillation of the latter will result in properly rotating the shaft 14, as will be apparent. A pivotally mounted dog or pawl 36 is further provided, a portion of the same being shown in Fig. 4, to prevent 70 reverse rotation of the shaft 14 when it is undesirable.

It will be apparent that while I have described and shown my device with more or less particularity, the same is susceptible of 75 many modifications and changes, and I do not wish to be restricted to the form shown or described beyond the scope of the appended claims.

What I claim is:—

1. In combination with a car having a dump door, a shaft, an arm rotatably mounted on said shaft, a second arm operatively connected to said door, said arms being pivotally connected, and an operating arm attached to said shaft and arranged to actuate said arms upon proper rotation of said shaft to close said door, said member being further arranged to support said door when in closed position.

2. In combination with a car having a dump door, a shaft, an arm rotatably mounted on said shaft, a second arm operatively connected to said door, said arms being pivotally connected, and an operating member 95 attached to said shaft and arranged to contact with one of said arms to close said door upon proper rotation of said shaft, said member being further arranged to contact with one of said arms to support said door 100 in closed position.

3. In combination with a car having a dump door, a shaft, an arm rotatably mounted on said shaft, a second arm operatively connected to said door, said arms being pivotally connected, and means carried by said shaft to actuate said arms to close said door, said means being also arranged to support said door when in closed position.

4. In combination with a car having a dump door, a shaft, an arm rotatably mounted on said shaft, a second arm operatively connected to said door, said arms being pivotally connected, and means carried by said shaft to actuate said arms to close said door, said means being also arranged to support said door when in closed position, said means being arranged to positively displace said arms from closed position when said shaft 115 is properly rotated.

5. In combination with a car having a dump door, a shaft, an arm rotatably mounted on said shaft, a second arm operatively connected to said door, said arms being pivotally connected, and an operating arm attached to said shaft and arranged to actuate said arms upon proper rotation of said shaft to close said door, said member being further arranged to support said door when 120 125 130

in closed position, said means being also arranged to coact with one of said arms and displace the same from closed position upon proper rotation of said shaft.

5 6. In combination with a car having a dump door, a shaft, an arm rotatably mounted on said shaft, a second arm operatively connected to said door, said arms being pivotally connected, a crank member attached to said shaft and arranged to actuate said first named arm upon proper rotation of said shaft to close said door, said second named arm being provided with a shoulder adapted to rest on said crank arm when said door is in closed position.

10 7. In combination with a car having a dump door, a shaft, an arm rotatably mounted on said shaft and constructed of spaced apart strips, a crank arm secured to said shaft and located between said strips, said crank arm being adapted to operate said first named arm on proper rotation of said shaft, and a second arm operatively connected to said door, said arm being pivotally connected to said first named arm and adapted to fit between the strips thereof when said door is in closed position, said last named arm being provided with a shoulder arranged to rest upon said crank arm when said door is in closed position.

15 8. In combination with a car having a dump door, a shaft, an arm rotatably mounted on said shaft and constructed of spaced apart strips, a crank arm secured to said shaft and located between said strips, said crank arm being adapted to operate said first named arm on proper rotation of said shaft, and a second arm operatively connected to said door, said arm being pivotally connected to said first named arm and adapted to fit between the strips thereof when said door is in closed position, said last named arm being provided with a shoulder arranged to rest upon said crank arm when said door is in closed position.

20 to fit between the strips thereof when said door is in closed position, said last named arm being provided with a shoulder arranged to rest upon said crank arm when said door is in closed position, said second 45 named arm being further provided with a portion lying adjacent said crank arm when in closed position, the latter being arranged upon proper rotation of said shaft to positively displace said second named arm from 50 closed position.

9. In combination with a car having a dump door, actuating means comprising a pair of pivotally connected arms, one of said arms having a shoulder, and a third arm 55 having a cam portion and mounted concentrically with respect to and arranged to actuate one of said first arms to effect closing of said doors, said shoulder of said arm being adapted to roll on said cam portion as 60 said doors approach closing position.

10. In combination with a car having a dump door, actuating means comprising a pair of pivotally connected arms, one of said arms having a shoulder, and a third 65 arm having a cam portion and mounted concentrically with respect to and arranged to actuate one of said first arms to effect closing of said doors, said shoulder of said arm being adapted to roll on said cam portion as 70 said doors approach closing position, said shoulderered arm and thereby said door being supported on said third arm when in closed position.

In testimony whereof, I have subscribed my name.

DAVID HINDAHL.
